LEWIS A. SAFFORD, OF BUFFALO, NEW YORK, ASSIGNOR TO BARCALO MANUFACTURING COMPANY, OF BUFFALO, NEW YORK.

DESIGN FOR A HANDLE FOR WRENCHES OR SIMILAR HAND-TOOLS.

59,786.

Specification for Design.

Patented Nov. 22, 1921.

Application filed October 17, 1919. Serial No. 331,485. Term of patent 14 years.

To all whom it may concern:

Be it known that I, LEWIS A. SAFFORD, a citizen of the United States, residing at Buffalo, in the county of Erie and State of New York, have invented a new, original, and ornamental Design for a Handle for Wrenches or Similar Hand-Tools, of which the following is a specification.

The accompanying drawing is a perspective view of a wrench having a handle embodying the design.

The handle is provided in its side face with depressions forming elongated, sunken panels disposed end to end, lengthwise of

the handle and separated by a transverse, raised portion, and narrow, marginal, raised portions which are flush with said transverse raised portion, and extend along the side edges of the panels and around the outer end of the handle.

I claim:

The ornamental design for a handle for a wrench or similar hand tools, substantially as shown and described.
